UNITED STATES PATENT OFFICE.

CORBAN H. ZILER, OF WINDSOR, ONTARIO, CANADA, ASSIGNOR OF ONE-HALF TO
LEGGETT & PLATT SPRING BED CO., LIMITED, OF WINDSOR, ONTARIO, CANADA,
A CORPORATION.

ART OF PRODUCING CLIPS AND THE LIKE.

1,407,977.

Specification of Letters Patent. Patented Feb. 28, 1922.

Application filed October 8, 1920. Serial No. 415,606.

To all whom it may concern:

Be it known that I, CORBAN H. ZILER, a citizen of the United States of America, residing at Windsor, in the county of Essex, 5 Province of Ontario, Canada, have invented certain new and useful Improvements in the Art of Producing Clips and the like, of which the following is a specification, reference being had therein to the accompanying 10 drawings.

This invention relates to the art of producing connecting members of curved formation and concurrently applying the same to the work in hand, and more particularly 15 to the production of connecting clips, links and the like, from a sheet metal blank and in a manner whereby such clips are given the desired curvature by the method of severance of the clip strip from the blank and 20 the application of the clip to another member or members brought into juxtaposition thereto, may be effected by such formation. With regard to the more specific application 25 of the invention, the same relates to the formation of clips for connecting the coils of wire springs in the construction of spring seats and the like, and to the application of such clips to such coils.

An object of this invention is to facilitate, 30 simplify and cheapen the manufacture of connecting members, such as clips, links and the like and also the application of such members to the work in hand. It is also an object of the invention to provide a clip and 35 a method of producing the same, which is such as to particularly adapt the same for use in the construction of fabricated structures, such as spring seats and back structures, and similar devices, and whereby the 40 clip forming and applying operations are so combined as to greatly facilitate and cheapen the manufacture of such device. Other objects will hereinafter more fully appear.

With the above and other ends in view, 45 the invention consists in the matters herein- after set forth and more particularly pointed out in the appended claims, reference being had to the accompanying drawing in 50 which—

Figure 1 is a front elevation of a device illustrative of means for performing the invention;

Fig. 2 is a longitudinal section through the same; 55

Fig. 3 is an elevation of the lower end portion of the device and illustrating the manner in which a clip is formed thereby and applied to spring coils;

Fig. 4 is a front elevation of the device 60 drawn to a reduced scale and showing a slightly modified construction and the manner in which the same is used in applying the clips to a spring structure;

Fig. 5 is a detail showing a further modification of the device and illustrating the manner in which a clip of a form different 65 from that shown in Fig. 3 may be formed; and

Fig. 6 is a view illustrative of different 70 forms of clips or connecting members which may be produced in accordance with the invention.

In the drawing an organized mechanism is illustrated for producing clips or similar 75 connecting members in accordance with the invention, which mechanism embodies the instrumentalities essential to the production of such members by the method embodying the invention, but it will be understood that 80 such organism is merely illustrative of one form of mechanism adapted to carry out the method which may be practiced by the employment of any suitable instrumental- 85

In the manufacture of spring seat cushions, and similar articles utilizing a plurality of helical springs, it is the common practice to connect the upper coils of the several springs by means of clips made of wire which are 90 formed prior to their application to the coils, thus necessitating means embodying a former for forming the clips and separate means for applying these clips.

In the present art of producing clips and 95 the like, these clips comprise strips severed from a blank or ribbon of sheet metal and the severing of the metal is performed in a manner to cause the strip during the cutting, to curl or bend in the direction of its length 100 and thus assume the desired permanent form. The strips are thus cut from the blank and coincidentally shaped, one at a time, and as the shaping is due to the manner of severance of the strips, no separate former, anvil 105 or other device for bending and setting the

clip stock is necessary, and by placing the spring coils or other members to be united or engaged by the clip, adjacent the portion of the blank being severed, as the end or ends 5 are cut free of the blank and curl or bend, the coils or member properly placed in relation thereto will be embraced thereby and permanently connected, the whole operation being automatic, and the only necessary instrumentalities being a suitable support for 10 holding the blank with an end portion projecting beyond the face of the support, a distance substantially equal to the width of the strip to be severed, and a suitable severing member movable across the support to 15 shear the projecting end portion from the blank, such shearing activity being progressive lengthwise of the strip being severed, thus supposedly causing, by the manner in 20 which the shearing force is applied, a change in the molecular structure of the strip which causes it to curl or bend as it is severed from the blank and assume the desired permanent curve or set.

25 In the drawing, instrumentalities necessary to the carrying out of the method embodying the invention are illustrated as embodied in an operable machine which consists as shown in Figs. 1 and 2 of a channeled 30 supporting or carrying member 1 having a slide or cutting member 2 slidable in the channel with its cutting end movable across a slot or opening 3 in the support adjacent its end and extending transversely of the 35 plane of reciprocation of the slide. The end portion of the cutter or slide which is adapted to move across the slot 3 is notched or otherwise shaped as at 4, to provide an angular cutting shoulder 5, all or a portion 40 of which shoulder is inclined in the direction of its length to the plane of reciprocation of the slide and the plane of the sheet metal blank 6 which is inserted in the slot 3 and supported thereby with an end portion 7 of the 45 blank projecting beyond the face of the support 1 and unsupported against lateral pressure, said free end portion 7 being of a width substantially equal to the desired width of the strip of stock to be severed.

50 In the construction shown in Figs. 1, 2 and 3, the cutting angles 5 are so formed relative to the plane of reciprocation of the slide that they are first brought into engagement with the side edges of the blank 55 and sever the strip from the blank progressively inward from said edges with a shearing action which curls the strip as it is severed and imparts a permanent set thereto. The narrow projecting end 7 of the blank 60 which is unsupported against lateral pressure of the cutter slide is thus progressively sheared from the body of the blank and this progressive shearing action causes the freed portions of the strip to curl in a direction 65 and with a curvature depending upon the

configuration of the end of the cutter slide or end surface which is formed with the hardened shearing angle 5 at its inner edge which edge or angle lies upon the surface of the support or member 1 beyond which the end portion 7 of the blank projects. This end surface may be variously shaped to secure the desired curvature of the severed strip and the configuration of the completed clip will depend upon the shape of 75 this end surface and upon the thickness of the stock of the blank and the width of its projecting end portion which is to be severed. The shape of the complete clip may therefore be varied by varying these elements 80 in relation to one another and the form of the clip may also be varied by the manner in which the strip is severed, that is, it may be cut from a blank by a shearing action progressing inwardly from each end of the 85 strip being severed, as shown in Figs. 1, 2 and 3, or it may be severed as indicated in Fig. 5, by cutting inwardly from each edge of the blank in opposite directions by opposed slides 8 and 9 moving in opposite directions and thus cause the opposite ends of the severed strip to curl in opposite directions. By severing the strip with a shearing action progressing longitudinally of the 90 strip from one end thereof another form of 95 clip may be produced and a clip in the form of a coil or with overlapping ends may be made by properly fashioning the cutting end of the slide.

In the production of any or all of the 100 various form of clips, loops, links or other connecting members having an eye or loop formation, the member or part to which the eye is to be connected or which is to be embraced by the eye, may be attached to or 105 inserted in the eye during the production of the clip or loop by simply positioning the member or members adjacent the end of the support 1 for the blank where the curling end or ends of the strip as it is severed from 110 the blank will curl around and embrace such member or members. The application of these clips or connecting members to the work in hand is therefore readily accomplished without the necessity for the use of 115 means separate from the cutter or severing instrumentality for forming and closing such eye or loop of the clip around the member.

This method of producing clips therefore 120 particularly adapts it for practice in connection with the fabrication of spring seats and the like which includes a large number of helical springs that are to be tied together by clips applied to the upper coils of adjacent springs as illustrated in Fig. 4 of the drawing wherein 10 indicates such coils of a series of springs. In Fig. 3 the manner of applying clips for uniting the coils 10 is 125 illustrated in detail.

As illustrated in Figs. 1 and 2, the cutter slide 2 is reciprocated on its power or downward stroke by a suitable rod 11 which may be continuously reciprocated by power in any suitable manner and this rod is provided with a head 12 which is reciprocable within the guideway of the supporting guide member 1 in longitudinal alinement with the slide 2. A block 13 is interposed in the guideway between the head 12 and slide 2 which block is normally held in a retracted position out of the path of reciprocation of the head 12 by a spring 14, and a manually operable pusher 15 is attached to the block to move the same into the path of the head against the action of the spring. To retract the slide 2 or move it on its idle stroke, a spring 16 is attached thereto at one end and at its opposite end is made fast in any suitable manner to the supporting guide member 1. The complete device illustrated, is of such a size that it may be readily grasped in the hand of the operator and accurately positioned by him relative to the work to which the clips are to be applied and when in proper position a clip may be caused to be formed by simply pressing inward upon the button or member 15 to move the block 13 into the path of head 12 so that upon downward movement of the head it will come into contact with the block and through such contact move the slide downwardly and sever a strip from the metal blank or ribbon which is fed through the slot 3 in the lower end of the supporting guide in any suitable manner, the inward movement of the blank being limited to gauge the width of the strip to be severed therefrom, by providing ribs 17 on the slide which project inwardly beyond the end face of the slide to engage the end of the blank adjacent each side edge thereof.

As previously stated the head 12 may be reciprocated in any suitable manner and as illustrated in Fig. 4, such reciprocation is effected by means of a rotatable cam 18 mounted upon the upper end of the supporting guide member 1 and made fast to a short shaft 19 which is preferably rotated by means of a flexible shaft 20 so that the device as a whole may be readily moved by the operator from place to place to permit him to locate the same in proper position relative to the coils 10 as shown in Fig. 4, to apply the clips 21 thereto as each is severed from the blank or ribbon which is also carried by the head or supporting guide 1.

The art of producing clips as set forth herein is therefore applicable to the manufacture of devices including a plurality of coiled springs wherein these springs are to be connected by clips or it will be understood that clips, links or other connecting members for other purposes may be advantageously produced in accordance with this invention and that these clips so produced

may be used independently or may be applied to the work in hand in accordance with this invention coincidently with their production.

Obviously any instrumentality may be employed for supporting a blank, from which the clip strips are to be sheared and any instrumentality may be employed in conjunction with such support for shearing the strips from the blank in accordance with the practice of the method herein set forth, and therefore it will be understood that the device shown in the drawing for practicing the invention is merely illustrative of simple means for such purpose. I do not therefore limit myself, except as set forth in the appended claims, to the employment of any particular form or arrangement of devices or means for practicing the invention.

What I claim is:

1. The method of producing connecting members of strip form from a blank and wherein the strip is curved in the direction of its length, which consists in supporting the blank with a portion substantially equal to the width of the strip to be produced projecting beyond the face of the support, and severing the projecting portion from the blank by a shearing action to cause the severed portion to curl in the direction of its length.

2. The method of producing connecting members of strip form from a blank and wherein the strip is curved in the direction of its length, which consists in supporting the blank with a portion projecting beyond the face of the support, and severing the projecting portion from the blank by a shearing action progressing inwardly from an edge thereof.

3. In the art of producing retaining clips and the like from a blank having one dimension which is greater than the width of a strip to be severed therefrom and wherein a portion of the clip is curved in the direction of the length of the clip strip; the method of producing a clip strip having a permanent curvature which consists in supporting the blank with a portion projecting beyond the face of the support a distance substantially equal to the width of the strip to be produced, and producing the strip by a shearing action with the shearing activity applied in a manner to develop the permanent strip curvature.

4. In the art of producing retaining clips and the like from a blank having one dimension which is greater than the width of a strip to be severed therefrom and wherein a portion of the strip is curved in the direction of the length of the clip strip; the method of producing a clip strip having a permanent curvature which consists in supporting the blank with a portion projecting beyond the face of the support a distance

substantially equal to the width of the strip to be produced, and producing a strip by a shearing action with the shearing activity progressively applied longitudinally of the strip.

5. In the art of producing retaining clips and the like from a blank having one dimension which is greater than the width of a strip to be severed therefrom and wherein
- 10 a portion of the clip is curved in the direction of the length of the clip strip; the method of producing a clip strip having a permanent curvature which consists in supporting the blank with a portion projecting beyond the face of the support a distance substantially equal to the width of the strip to be produced, and producing the strip by shearing action applied progressively inward from an edge of the blank corresponding to an end of the strip being severed therefrom.
6. In the art of producing retaining clips and the like from a blank having one dimension which is greater than the width of
- 25 a strip to be severed therefrom and wherein a portion of the clip is curved in the direction of the length of the clip strip; the method of producing a clip strip having a permanent curvature which consists in supporting the blank with a portion projecting

beyond the face of the support a distance substantially equal to the width of the strip to be produced, and concurrently producing the strip and its curvature by shearing the blank to sever the strip therefrom with the 35 shearing action developed progressively in the direction of the length of the strip from an end thereof.

7. In the production of fabricated articles wherein elements are connected by members 40 of strip form which are bent to embrace adjacent portions of such elements, and wherein in the stock from which such member is to be formed comprises a projecting end portion of a supported blank; the method of 45 applying the member which consists in producing the strip by a shearing action while the blank and element to be embraced by the formed member are in juxtaposition, with the shearing action developed progressively 50 inward from an edge of the blank to concurrently produce a curvature of the strip and cause the same to embrace said element.

In testimony whereof I affix my signature in presence of two witnesses.

CORBAN H. ZILER.
